UNITED STATES PATENT OFFICE

2,658,750

AWNING TYPE WINDOW

Arthur H. Soule, San Marino, Calif., assignor to
Continental Specialties Company, Ltd., Los Angeles, Calif., a corporation of California

Application October 6, 1951, Serial No. 250,136

3 Claims. (Cl. 268—21)

1

This invention relates to a multiple sash window construction of the louver type.

The main object of the present invention is to provide a multiple sash window construction having novel means for opening and closing the sashes.

A more particular object of the present invention is to provide a multiple sash window construction having a plurality of banks of multiple sash units, in which window construction there are spring means urging the sashes toward open positions and which window construction further includes a manually operable mechanism for closing the sashes of all the banks against the resistance of the spring means.

Various other objects will be apparent from the following description taken in connection with the accompanying drawings wherein:

Figure 1 is a front view in elevation of a multiple bank window frame construction incorporating the concepts of the present invention;

Figure 2 is a fragmentary sectional view taken along line 2—2 of Figure 1;

Figure 3 is a fragmentary vertical sectional view taken along line 3—3 of Figure 1 and showing the sash-operating mechanism;

Figure 4 is a vertical sectional view taken along line 4—4 of Figure 1, showing the tension springs for urging the sashes toward their open positions;

Figure 5 is a view similar to Figure 4, but showing the sashes in their open positions;

Figure 6 is a fragmentary horizontal view taken along line 6—6 of Figure 4.

Referring to the accompanying drawings, wherein similar reference characters designate similar parts throughout, the arrangement in Figure 1 includes a window frame, generally entitled 9, having a sill 11, a head 13, jambs 15 and 17 and mullions 19 and 21. Frame 9 is thus divided for the reception of three banks of sashes, generally entitled 23, 25 and 27, which are adapted to be operated in unison.

The sashes of each bank are mounted for swinging movement about horizontal axes. The manner of swingably mounting the sashes may take many forms, but the preferred form is shown in Figures 4, 5 and 6. As shown in Figure 4, each sash is swingably connected to the window frame by a pair of armplates 29, only one of

2

which is shown for each sash, each armplate being pivotally mounted at its outer or upper end to its sash and being pivotally connected at 31 to the associated jamb or mullion depending upon the location of the armplate. Each sash is also connected to the window frame by a pair of sash plates 33, only one of which is shown for each sash, each sash plate being fixedly connected at one of its ends to the upper end of its sash and being pivotally connected at its opposite end at 35 to a shoe 36 which is fixedly secured to a continuous traveling track 39 slidably received within a channel provided in the associated jamb or mullion depending upon the location of the particular continuous traveling track. As is apparent from Figures 4 and 5, the traveling tracks interconnect the sashes of each bank so that the sashes swing in unison from open to closed positions and vice versa.

Each sash is urged toward its open position by a pair of tension springs 41 connecting sash plates 33 to pivots 31 mounted on the jambs or mullions. Only one tension spring is shown for each sash. The tension springs are obviously under tension in the positions in which they are disposed in Figure 4 and are also under tension, but of a lesser degree, in the positions disclosed in Figure 5, so that the sashes are firmly disposed in their open positions.

Sash-operating mechanism is provided for closing the banks of sashes in unison with one another against the resistance of the tension springs 41 and for progressively releasing the sashes for opening movement under the influence of tension springs 41. This operating mechanism is best shown in Figures 1, 2 and 3 and comprises a common cable drive shaft 43 rotatably extending through the mullions 19 and 21 and into jambs 15 and 17 and being rotatably supported in these various members by suitable bearings 45 (see Figure 2). Cable drive shaft 43 has secured thereto therealong cable spools 47 disposed adjacent the jambs and mullions and carrying cables 49, each being secured at one end to its spool and at the other end to the lower end of the associated lower sash by a screw 51. For rotating common cable drive shaft 43, there is provided an encased worm gear drive 53 including a worm wheel 55 secured to cable drive shaft 43 (see Figure 2) and a worm 57 in

driving engagement with worm wheel 55. Worm gear drive 53 is mounted on sill 11 by a suitable bracket 59, compare Figures 2 and 3. Worm 57 is mounted on a vertical drive shaft 61 extending through the sill 11 and down into a wall 63 below the frame 9 and connected by a universal joint 65 to a drive stud 67 mounted in a crank box 69 provided in wall 63. The drive stud has a depending non-circular end which is adapted to fit into a crank and by which the worm drive shaft 61 can be rotated to thereby rotate cable drive shaft 43. It is obvious that the worm gear drive 53 is a self-locking drive in that it can not be driven from the worm to the worm but only from the worm to the worm wheel and therefore the sashes will remain in any position in which they are adjusted by rotation of cable drive shaft 43.

The operation of the window frame construction is as follows. In the position of the parts shown in Figure 4, the tension springs 41 are under considerable tension urging the sashes to swing outwardly to the positions shown in Figure 5. A suitable crank not shown can be inserted into the crank box and through the mechanism previously described, the cable drive shaft 43 can be rotated in a direction to unwind the cables 47 from the cablespools 47 to progressively release the sashes for outwardly swinging movement. Although the sashes are shown in their completely open positions in Figure 5, it is obvious that the cranking operation could be terminated at any point and the sashes would remain in such position because of the non-reversible drive through the worm gear drive 53. When it is desired to close the windows, the operating crank is again inserted into the crankbox and the drive stud rotated to reversely rotate the cable drive shaft and wind up the cables 47 pulling the sashes inwardly so as to close the sashes. It is obvious that since the sashes are interconnected vertically by the traveling tracks 39, and horizontally by the common cable drive shaft 43, all the sashes of the entire window construction will move in unison from open to closed positions.

Although two tension springs have been disclosed for each sash, it is contemplated that a pair of very heavy coil springs could be connected at one set of ends to the opposed tracks of a bank of sashes and at their other set of ends to the jambs or mullions, thereby providing only two springs for each bank of sashes. Such construction is to be considered an equivalent of that shown in the drawings.

By the present invention, a window frame construction has been provided including a plurality of sashes all operable in unison, said sashes being readily opened and closed by the simple operation of a single mastercrank which can be inserted into the crankbox 69.

Although a worm gear drive has been shown for cable 49, the invention is not intended to be limited by this disclosure since there are many other types of possible operators, including screw, slide, etc. which may be considered as equivalent to the worm gear drive. Furthermore, the operator for the cable can be mounted in various places about the window, and the mounting on the sill of gear drive 53 is not intended to be a limitation but only illustration of a practical application of the present invention.

While I have shown the preferred form of my invention, it is to be understood that various changes may be made in this construction by

those skilled in the art without departing from the spirit of the invention as defined in the appended claims.

Having thus described my invention, what I claim and desire to secure by Letters Patent is:

1. A window construction, comprising a window frame, at least two banks of sashes in the window frame, each bank comprising a plurality of vertically adjacent sashes mounted in the frame for swinging movement about horizontal axes from open to closed positions and vice versa, the sashes of each bank being interconnected for movement in unison, spring means urging the sashes to assume open positions, and means for closing all of the sashes in unison against the resistance of the spring means, the last named means including a common cable drive shaft carrying a cable for each bank of sashes, the cable for each bank being connected at one end to the lower end of the lower sash and at its opposite end to the common cable drive shaft, and means for rotating said cable drive shaft for optionally opening or closing the sashes depending upon the direction of rotation of the common drive shaft.

2. A window construction, comprising a window frame, at least two banks of sashes in the window frame, each bank comprising a plurality of vertically adjacent sashes mounted in the frame for swinging movement about horizontal axes from open to closed positions and vice versa, the sashes of each bank being interconnected for movement in unison, spring means urging the sashes to assume open positions, and means for closing all of the sashes in unison against the resistance of the spring means, the last named means including a common cable drive shaft carrying a cable for each bank of sashes, the cable for each bank being connected at one end to the lower end of the lower sash and at its opposite end to the common cable drive shaft, means for rotating said cable drive shaft for optionally opening or closing the sashes depending upon the direction of rotation of the common drive shaft, and means for locking the sashes in any position of adjustment.

3. A window construction, comprising a window frame, at least two banks of sashes in the window frame, each bank comprising a plurality of vertically adjacent sashes mounted in the frame for swinging movement about horizontal axes from open to closed positions and vice versa, the sashes of each bank being interconnected for movement in unison, spring means urging the sashes to assume open positions, and means for closing all of the sashes in unison against the resistance of the spring means, the last named means including a common cable drive shaft carrying a cable for each bank of sashes, the cable for each bank being connected at one end to the lower end of the lower sash and at its opposite end to the common cable drive shaft, and means for rotating said cable drive shaft for optionally opening or closing the sashes depending upon the direction of rotation of the common drive shaft, the last-named means assuming the form of a non-reversible drive whereby the sashes are automatically locked in any position of adjustment.

ARTHUR H. SOULE.
